(57) **CLAIM**

The ornamental design for a multi-surface controller, as shown and described.

DESCRIPTION

FIG. 1 is a perspective view of the ornamental design for a multi-surface controller;

FIG. 2 is a left view thereof;

FIG. 3 is a right view thereof;

FIG. 4 is a front view thereof;

FIG. 5 is a rear view thereof;

FIG. 6 is a top view thereof; and,

FIG. 7 is a bottom view thereof.

The broken lines showing of the remainder of the multi-surface controller are for environmental purposes only and form no part of the claimed design.

1 Claim, 4 Drawing Sheets

FIG. 1

FIG. 3

FIG. 2

FIG. 4

FIG. 5

FIG. 6

FIG. 7
